(57) **CLAIM**

The ornamental design for a cleaning brush as shown and described.

DESCRIPTION

FIG. 1 is a perspective view of a cleaning brush showing the claimed design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a view of the claimed design covered with the brush thereof.

The broken lines depict portions of the cleaning brush that form no part of the claimed design.
